(57) **CLAIM**

The ornamental design for a wireless earbuds, as shown and described.

DESCRIPTION

FIG. 1 is a rear, left and bottom perspective view of a first embodiment of a wireless earbuds, showing my new design; FIG. 2 is a front, right and top perspective view thereof; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom plan view thereof; FIG. 9 is an enlarged view of an encircled portion of the wireless earbuds labeled 9 in FIG. 2; FIG. 10 is an enlarged view of an encircled portion of the wireless earbuds labeled 10 in FIG. 2; FIG. 11 is a rear, left and bottom perspective view of a second embodiment of a wireless earbuds; FIG. 12 is a front, right and top perspective view thereof; FIG. 13 is a front view thereof; FIG. 14 is a rear view thereof; FIG. 15 is a left side view thereof; FIG. 16 is a right side view thereof; FIG. 17 is a top plan view thereof; FIG. 18 is a bottom plan view thereof; FIG. 19 is an enlarged view of an encircled portion of the wireless earbuds labeled 19 in FIG. 12; FIG. 20 is an enlarged view of an encircled portion of the wireless earbuds labeled 20 in FIG. 12; FIG. 21 is a rear, left and bottom perspective view of a third embodiment of a wireless earbuds; FIG. 22 is a front, right and top perspective view thereof; FIG. 23 is a front view thereof; FIG. 24 is a rear view thereof; FIG. 25 is a left side view thereof; FIG. 26 is a right side view thereof; FIG. 27 is a top plan view thereof; FIG. 28 is a bottom plan view thereof;

(Continued)

FIG. 29 is an enlarged view of an encircled portion of the wireless earbuds labeled 29 in FIG. 22; and, FIG. 30 is an enlarged view of an encircled portion of the wireless earbuds labeled 30 in FIG. 22.

The evenly dashed broken lines illustrate portions of the wireless earbuds that form no part of the claimed design. The dash-dot broken lines encircling portions of the wireless earbuds illustrated in enlargements form no part of the claimed design.
